UNITED STATES PATENT OFFICE.

FRANK WESBECHER, OF AKRON, OHIO, ASSIGNOR TO HIMSELF AND CHARLES E. HOEFEL, OF AKRON, OHIO.

SINK STRAINER.

Application filed January 20, 1928. Serial No. 248,097.

This invention relates to new and novel improvements in strainers and similar utensils and has particular reference to a utensil of improved construction adapted to be used 5 as a sink strainer.

Sink strainers of known construction are ordinarily formed of a material which will rust, corrode or otherwise deteriorate thereby causing an unsightly discoloration of the 10 sink in which the same is used.

Objects of this invention are to provide a sink strainer of simple, durable construction which may be manufactured at a relatively low cost and which may be used 15 indefinitely without causing discoloration of the sink.

Other objects are to provide a sink strainer composed of hard rubber or other like material and to provide corrugated side walls 20 which will materially strengthen the structure and which will permit the liquid to drain from the waste material deposited therein.

An additional object is to provide a sink 25 strainer of rigid material having new and improved cushion legs therefor whereby the same will be supported in spaced relation to the bottom of the sink and to thereby provide a strainer which will not scratch, mar, 30 stain or otherwise injure the sink.

The above objects are accomplished and additional ends are attained by the novel construction, combination and arrangement 35 of parts hereinafter described and illustrated in the accompanying drawing in which I have shown a preferred form of the invention, it being understood that the invention is capable of various adaptations and that changes and modifications may be 40 made or resort had to substitutions which come within the scope of the appended claims.

In the drawings like characters are used 45 to designate like parts as the same may appear in any of the several views and in which:—

Figure 1 is a perspective view of a strainer constructed in accordance with this invention,

50 Figure 2 is a top plan view of same,

Figure 3 is an enlarged cross sectional view taken as indicated by the lines 3—3 of Figure 2.

Proceeding now to a detailed description 55 of the invention with reference to the draw-

ings, the bottom wall 5 and the side wall 6 are composed of a single piece of hard rubber or similar material. The bottom wall 5 is provided over its entire area with a multiplicity of openings 7. The side walls 6 are 60 corrugated to provide the vertical grooves 8 on the interior face thereof and the corresponding grooves 9 on the outer face thereof. The construction is such that when a quantity of fruit parings or other refuse 65 is stacked against the side wall 6, it will be held away from the grooves 8 and permit liquid to drain downwardly and escape through the openings 7. The bottom wall 5 is also provided with a plurality of circular 70 openings 10 which are substantially larger than the openings 7 and which serve as a seat for the rubber legs 11. Each leg 11 is provided with an enlarged knob 11^a which is adapted to seat in the bottom of the sink. 75 The reference character 11^b denotes a cylindrical neck which is adapted to fit in the bore 10 and the reference character 11^c denotes a head which is formed on the upwardly projecting end of the neck 11^b. The 80 legs 11 are preferably formed of soft, elastic rubber and are secured to the bottom 5 by forcing the head 11^c into one of the openings 10. As the head 11^c is composed of soft rubber, it is easily displaceable and can be 85 forced through the openings 10 and will expand to engage the upper face of the bottom 5, thereby detachably securing the legs 11 to the strainer.

It will be seen that the legs 11 may be 90 easily removed, cleaned and replaced when desired. The strainer is preferably molded of one piece of hard rubber, but may be formed to any degree of hardness desired or molded of any suitable material. The 95 side wall 6 is provided around the upper edge thereof with a facing 12 of soft elastic rubber. As the entire structure is molded and vulcanized in a mold, a soft rubber compound is placed in the mold to form the 100 relatively soft edge 12, and the edge 12 is vulcanized in the same mold thereby forming a side wall 6 of hard rubber having an integrally formed soft rubber edge 12.

If desired, the legs 11 may be formed of 105 a soft rubber compound and positioned in the mold to secure the same to the bottom wall 5 by vulcanization.

In use, the strainer is positioned in a sink in the ordinary manner. The soft rubber 110

legs 11 serve to protect the sink and as the main body of the strainer is composed of hard rubber, it will not deteriorate and cause any discoloration of the sink. When

5 it is desired to empty material from the strainer, it may be inverted and the edge 12 may be struck on a relatively hard surface without injuring the side walls 6.

It will thus be seen that I have provided 10 a strainer of simple construction which may be manufactured at a low cost and which will be very efficient in use.

Having thus illustrated my invention and described the same in detail, what I claim 15 is new and desire to secure by Letters Patent is:—

1. In a sink strainer, a bottom wall and side walls composed of one piece of hard rubber, a multiplicity of openings in said 20 bottom wall, said side walls being vertically corrugated and having an upper edge portion composed of soft rubber formed integrally therewith.

2. In a sink strainer, a bottom and side 25 walls composed of one piece of relatively stiff rubber composition, a multiplicity of

openings in said bottom wall, said side walls terminating around the upper edge thereof with the soft rubber portion formed integrally therewith.

3. In a sink strainer of the class described, a bottom wall and side walls formed of one piece of relatively stiff composition, the side walls provided around the upper edge thereof with a soft rubber portion formed in- 35 integrally therewith.

4. In a sink strainer, in combination a bottom wall and side walls composed of one piece of relatively stiff rubber composition, a multiplicity of openings in said bottom wall, said side walls being vertically corrugated and having an upper edge portion composed of soft rubber formed integrally therewith, said bottom walls provided with additional openings adjacent 40 each corner thereof and legs composed of relatively soft rubber fitted in said opening.

In testimony whereof I have hereunto set my hand.

FRANK WESBECHER.
